(57) **CLAIM**

The ornamental design for a bucket, as shown and described.

DESCRIPTION

The patent or application file contains at least one drawing executed in color. Copies of this patent or patent application publication with color drawing(s) will be provided by the Office upon request and payment of the necessary fee.

FIG. 1 is a top-front perspective view of a bucket showing my new design in a first condition of use;

FIG. 2 is a top view thereof in a second condition of use;

FIG. 3 is a top view thereof in a third condition of use;

FIG. 4 is a top view thereof in a fourth condition of use;

FIG. 5 is a side view thereof with a handle in a first position;

FIG. 6 is a side view thereof with the handle in a second position; and,

FIG. 7 is a front-top side perspective view thereof.

The bottom view of the bucket is disclaimed because it is not visible during normal use. The side views are mirror images of each other.
